HOLDER FOR ROLLED MATERIAL

Carl A. Laystrom, Evanston, and Howard R. Sigler, Argenta, Ill., assignors, by mesne assignments, to Faries Manufacturing Company, Chicago, Ill., a corporation of Illinois

Application April 16, 1947, Serial No. 741,768

3 Claims. (Cl. 242—55.2)

1

This invention relates to improvements in a holder for rolled material. More particularly the invention relates to a holder of the type commonly used in bathrooms for holding rolls of toilet paper.

While the roller of this invention is particularly well adapted to hold rolls of toilet paper, it is to be understood that this invention is not limited to such use being generally useful for holding any rolled material, for example, rolled paper hand towels and rolls of wrapping paper and the like.

Of the holders for toilet paper now in use, one of the most popular types makes use of a shaft having movable sections which may be telescoped over each other when a roll of toilet paper is positioned thereon or removed therefrom. Other types provide a spring-pressed member in the middle of the shaft or at one end. In each of these paper holders it is difficult to adjust the shaft to prevent scratching of the fixture when the roll is replaced. A further disadvantage lies in the fact that it is difficult, and in most cases impossible, to remove the shaft from its supporting members when all the paper has been removed from the cardboard center core without first tearing open this core. These cores are usually made of heavy cardboard not easily torn without the aid of a knife.

In the paper holder of the present invention all of these disadvantages are overcome by the use of a shaft having spring-pressed, ball shaped members at both ends. This shaft permits easy adjustment for insertion into the fixture and the ball shaped end members afford a means for withdrawing the member by pulling outwardly on the empty center core of the paper roll, without first tearing open this core.

It is accordingly an important object of this invention to provide a paper holder which may be quickly and easily adjusted for insertion in supporting members.

Another object of this invention is to provide a paper holder which may be removed from its supporting members without first removing the center core of the paper roll.

A further object of this invention is the provision of a paper holder which may be removed from its supporting members by merely pulling outwardly on the shaft.

Another and further object of this invention is to provide a paper holder having a shaft the parts of which may be telescoped by the outward movement of the shaft itself.

According to the general features of this in-

2

vention there is provided a paper holder having a center shaft which is equipped with members having semi-spherical outer end portions, said members being spaced apart and pressed outwardly into sockets in supporting arms by a common center spring which is enclosed inside the shaft.

Other and further objects, features and advantages of this invention will be evident to one skilled in the art from the following detailed description taken in connection with the annexed sheet of drawings, on which:

Figure 1 is a plan view of a holder of this invention;

15 Figure 2 is a sectional view taken substantially on line II—II of Figure 1 looking in the direction indicated by the arrows; and

20 Figure 3 is a fragmentary sectional view similar to Figure 2 and showing a modified form of 20 the holder of this invention.

In Figs. 1 and 2 reference numeral 10 is a rotatable shaft supported at either end in a bracket or support arm 11.

The shaft 10 comprises a substantially cylindrical member 13 having a central aperture 13a extending from one end to the other therein. At each end the member 13 is bent inwardly to form an annular flange portion 13b which is arranged to limit the outward movement of a telescoping end member 14.

The end members 14 are each adapted to be positioned in a semi-spherical shaped socket 11a of the bracket 11 for supporting the shaft. Each member 14 comprises a cylindrical portion 14a which is adapted to slide in the central core 13a of the shaft 13. A forward semi-spherical end portion 14b is joined to the cylindrical portion 14a by means of a transition section 14c thus affording an outside shoulder portion 14d and an inside shoulder portion 14e. A spring member 15 is arranged inside the shaft 13 to abut at either end against the inside shoulder portions 14e of the members 14 and to move the members 14 outwardly. The annular flange 13b acts as a limit to the outward movement of the members 14.

Thus it is seen, in Fig. 2, that there is provided in this invention a center shaft having members with semi-spherical end portions disposed at either end inside of said shaft and arranged to be urged outwardly against a limiting flange 13b of the shaft 13.

It is to be noted that the spring 15 is used to move the end members 14 outwardly against the 55 annular flanges 13b as a limit. Under these con-

ditions the tightness or looseness of the fit of the shaft assembly in the support arms 11 will not depend upon the spring 15 but rather upon the correct positioning of the supporting arms 11.

In Fig. 3 is shown a modification in which there is provided a substantially cylindrical portion 14f between the front ball-shaped member 14g and the transition portion 14h. With this arrangement the spring 15 does not urge the member 14' against the edge of the ring 13b as a stop but is instead used to press the members 14' into the sockets 11b provided in the support arms 11. In this modification the positioning of the shaft 13 in the support arms is more positive than is the arrangement of Figure 2.

Also shown in Fig. 3 is a substantially cylindrical aperture 11b in the support arm 11 instead of the oval socket 11a of Fig. 2. Either socket, 11b or 11a, may be provided as desired.

To position the shaft in the holder between the holder arms 11, the member 14 at one end of the shaft, for example the left end as viewed in Fig. 2, is positioned in the socket of the support arm 11 while the member 14 at the right end of the shaft is depressed. The shaft is then swung inwardly between the support arms until the member 14 at the right end of the shaft is substantially opposite the socket in the support arm 11 at which time the member 14 is released. The member 14 will be urged outwardly by the spring 15 into the socket.

The shaft 13 may be withdrawn from between the support arms 11 merely by pulling outwardly on the shaft portion 13. This outward movement will automatically cause the end members 14 to telescope into the shaft and allow the shaft to come outwardly. However, if the support arms 11 are made of a material that may be scratched, the shaft 13 may best be withdrawn from between the support arms by pulling outwardly at one side of the shaft thus moving the member 14 outwardly at that side only and causing the member 14 at that end to telescope into the shaft 13. When the outermost edge of the ball point end of the member 14 is substantially opposite the lower edge of the socket, a person's finger may be inserted on top of the ball point and the member 14 held in this depressed position while the shaft 13 is swung outwardly and the other end removed from its socket.

Thus there is provided in this invention a holder having a shaft which is easily adjusted for positioning between the support arms and which is easily removed by an outward pull on the shaft 13 either in the middle or at one end.

It will, of course, be understood that various details of construction may be varied over a wide range without departing from the principles of this invention, and it is therefore not the pur-

pose to limit the patent granted hereon other than necessitated by the scope of the appended claims.

We claim as our invention:

1. A holder for rolled material comprising a hollow cylindrical shaft, a pair of support arms having oppositely disposed segmental spherical sockets, a cylindrical end member telescopically received in each end of said shaft in guided sliding contact with the inner wall of said shaft and having a closed spherical end adapted to be disposed in one of said sockets of said support arms, said shaft having at its ends inwardly bent annular flanges to limit the outward movement of said end members axially of said shaft, and a single spring disposed inside said hollow shaft and extending into said end members for urging said end members into said sockets.

2. A holder for rolled material comprising a hollow cylindrical shaft, a pair of support arms having oppositely disposed sockets, a cylindrical end member telescopically received in each end of said shaft in guided sliding contact with the inner wall of said shaft and having a closed rounded end adapted to be disposed in one of said sockets of said support arms, said shaft having at its ends inwardly bent annular flanges to limit the outward movement of said end members axially of said shaft, and a single spring disposed inside said hollow shaft and extending into said end members for urging said end members into said socket.

3. An article of manufacture, a paper roll-mandrel comprising a hollow cylindrical shaft, a cylindrical end member telescopically received in each end of said shaft in guided sliding contact with the inner wall of said shaft and having a closed spherical end, said shaft having at its ends inwardly bent annular flanges to limit the outward movement of said end members axially of said shaft, and a single spring disposed inside said hollow shaft in abutting contact with said end members for urging said end members axially outwardly of said shaft.
